(No Model.)

J. P. MARSH.
AIR VALVE FOR RADIATORS.

Patented Nov. 10, 1891.

No. 462,845.

UNITED STATES PATENT OFFICE.

JAMES P. MARSH, OF CHICAGO, ILLINOIS.

AIR-VALVE FOR RADIATORS.

SPECIFICATION forming part of Letters Patent No. 462,845, dated November 10, 1891.

Application filed April 30, 1891. Serial No. 391,052. (No model.)

To all whom it may concern:

Be it known that I, JAMES P. MARSH, a citizen of the United States, residing at Chicago, in the county of Cook and State of Illinois, have invented certain new and useful Improvements in Air-Valves for Radiators, of which the following is a specification, reference being had to the accompanying drawings, which are made a part hereof, and in

to which—

Figure 1 is an axial section of the improved valve when open for the escape of air. Fig. 2 is a similar view thereof when closed by the presence of heat in the casing. Fig. 3 is a similar view thereof when closed by the presence of water in the casing. Fig. 4 is a horizontal section thereof on the line 4-4, Fig. 1. The scale of the drawings is a trifle less than two to one.

The present invention relates to a valve to be applied to radiators for the purpose of permitting cold air to escape from them, in order to give place to the steam; and the object of the said invention is to provide a valve that will not only permit the air to escape and prevent the escape of steam, but that will also effectually prevent the escape of water.

To this end the invention consists in certain features of novelty that are particularly pointed out in the claims hereinafter.

Referring to the drawings, A represents the base of the valve, having an externally-screw-threaded projection, a , designed to be tapped into the radiator. Upon the top side of this base is an internally-threaded annular flange a' , to which is screwed the cylindrical shell or casing B, the dome of which latter is provided with an opening threaded at b for engaging a correspondingly-threaded screw C, and with a counterbore b' for receiving a gasket D and the enlarged head of the screw, by which said gasket is compressed around the screw, so as to form a steam-tight joint. The screw C is provided with a duct c , that passes completely through it, forming the vent or outlet of the casing, and with a counterbore c' at its inner end.

E is a post of vulcanite or similar expansive material, which is preferably hollow for the greater part of its length and has its lower end forced into an annular groove a'' , formed in the top of the base A.

F is a metal float of inverted-cup shape, which normally rests with its closed end on the top of the post E, whence it extends downward nearly to the base A, surrounding the post.

G is a needle-valve secured to the top of the float and terminating in operative proximity to a seat formed for it at the entrance to the outlet c , said valve being adapted to close said outlet whenever steam or water enters the casing through the inlet a'' , which is formed in the base A and communicates with the interior of the radiator.

The parts are so proportioned and arranged that when the radiator is cold they will occupy the positions in which they are shown by Fig. 1, the outlet c being open. When steam is admitted to the radiator, the cold air is expelled therefrom, passing through the duct a'' into the valve-casing and through said casing, as indicated by the arrows, escaping through the outlet c .

When all of the cold air has been thus expelled from the radiator and steam enters the valve-casing, the vulcanite post E becomes heated and expands, and in so doing elevates the float F, and with it the valve G, closing the outlet, as shown in Fig. 2.

It sometimes happens, however, that the radiator contains more or less cold water, and that before the steam enters the valve-casing and causes the outlet to be closed, as just described, more or less of said water finds its way into the valve-casing and would eventually escape through the outlet c if the latter were not closed.

With the arrangement shown in the drawings, before the level of the water in the casing has reached the outlet the float F is lifted and carries the valve G up, closing the outlet, as shown in Fig. 3.

The flow being thus checked, the water in the radiator will regain its equilibrium, whereupon the water will flow from the valve-casing back into the radiator, and the float and valve will fall by gravity to the position shown in Fig. 1. The discharge of air through the outlet c will then be resumed and will continue until again interrupted by the presence of either steam or water in the casing, as described.

In order to prevent the air or steam as it enters the valve-casing from blowing the float from its seat and thus prematurely closing

- the outlet, the discharge end of the inlet duct a^3 is situated at one side of the float, so that it cannot discharge directly beneath the float. As a further precaution a shield is placed between the inlet and float. This shield preferably consists of a jacket II, which surrounds the float, and is preferably formed at bottom with an offset h , that rests upon the base A, and a contracted portion h' , that occupies the annular groove a^2 and surrounds the lower end of the post E. This jacket is of such diameter that but little space is left between it and the casing B, and to provide for the free upward passage of the air or steam a crimp or groove h^2 is formed in its side opposite the inlet a^3 . It is also provided at or near its bottom, and preferably opposite the inlet a^3 , with an opening h^3 , through which water may escape.
- 20 The entrance to the outlet c is situated some distance below the ceiling of the casing, so that the air or steam that strikes against the ceiling will be compelled to pass in a downward direction before it can enter said outlet, as indicated by the arrows, and as a consequence any water that it may carry with it will be precipitated and fall into the jacket II, whence it may flow through opening h^2 into the duct a^3 and back into the radiator.
- 25 In order to increase the superficial area of the post E it is made hollow, and in order to admit heat to its interior it is provided with one or more lateral perforations e.
- By providing the finer end of screw C with 30 counterbore c' , it acts as a guide for the valve G and insures its proper seating.
- Having thus described my invention, the following is what I claim as new therein and desire to secure by Letters Patent:
- 35 1. The combination, with the casing having an inlet and an outlet, of a post of expansive material, an independently-movable float resting normally upon said post, and a valve carried by said float and adapted to close the outlet when moved either by the expansion of the post or by the presence of water in the casing, the inlet being located so as not to discharge into or beneath the float, substantially as set forth.
- 40 2. The combination, with the casing having an inlet and an outlet, of a post of expansive material, an independently-movable float sur-

rounding and adapted to rest upon said post, and a valve carried by said float and adapted to close said outlet, the inlet being located so as not to discharge into or beneath the float, substantially as set forth. 55

3. The combination, with the casing having an inlet and an outlet, of a post of vulcanite, an independently-movable float of inverted-cup shape surrounding and adapted to rest upon said post, said float extending nearly to the base of the casing, and a valve carried by said float and adapted to close said outlet, the inlet being located so as not to discharge into or under the float, substantially as set forth. 60

4. The combination, with the casing having an inlet and an outlet, of a float, a valve carried thereby and adapted to close said outlet, and a shield situated between the inlet and float, so as to prevent it from discharging into or beneath the float, substantially as set forth. 65

5. The combination, with the casing having an inlet and an outlet, of a float, a valve carried thereby and adapted to close said outlet, and a shield surrounding the float and having an opening for the passage of water, the inlet being arranged to discharge into the casing upon the outside of the shield, substantially as set forth. 75

6. The combination, with the casing having the inlet and the outlet, of the post E of expansive material, the cup-shaped float F, surrounding and resting upon said post, the valve G, carried by said float and adapted to close the outlet, and the shield II, surrounding the float and having the opening h^3 , substantially as set forth. 85

7. The combination, with the base A, having the inlet a^3 , and the shell B, having the outlet c, of the post E, having its lower end secured to the base, the cup-shaped float F, surrounding and adapted to rest upon said post, the valve G, carried by said float and adapted to close said outlet, and the shield II, having the contracted portion h' , said base having an annular groove a^2 for receiving said contracted portion, substantially as set forth. 90

JAMES P. MARSH.
